UNITED STATES PATENT OFFICE.

JASPER R. ANDERSON, OF FARGO, NORTH DAKOTA.

DESIGN FOR A NECKTIE HOLDER.

Application filed January 18, 1923. Serial No. 4,929. Term of patent 3½ years.

To all whom it may concern:

Be it known that I, JASPER R. ANDERSON, a citizen of the United States of America, residing at Fargo, in the county of Cass and State of North Dakota, have invented a new, original, and ornamental Design for Necktie Holders, of which the following is a specification, reference being had to the accompanying drawing, forming part thereof.

I claim:

The ornamental design for a necktie holder as shown.

In testimony whereof I affix my signature.

JASPER R. ANDERSON.
